UNITED STATES PATENT OFFICE.

JOHN M. HOWARD, OF MEDIA, PENNSYLVANIA, AND CHARLES J. ALLEN, OF MOORESTOWN, NEW JERSEY.

DESIGN FOR TRACTOR TRANSMISSION-HOUSING.

58,236.

Specification for Design. Patented June 28, 1921.

Application filed June 18, 1920. Serial No. 390,041. Term of patent 14 years.

To all whom it may concern:

Be it known that we, JOHN M. HOWARD and CHARLES J. ALLEN, citizens of the United States, residing, respectively, in Media, in the county of Delaware and State of Pennsylvania, and in Moorestown, in the county of Burlington and State of New Jersey, have invented a new, original, and ornamental Design for Tractor Transmission-Housing, of which the following is a specification, reference being had to the accompanying drawing, forming part thereof.

In the said drawing Figure 1 and Fig. 2 are perspective views respectively showing the left and right hand sides of a tractor transmission housing embodying our new design, and Fig. 3 and Fig. 4 are respectively front and rear perspective views thereof.

We claim:

The ornamental design for tractor transmission housing, as shown.

JOHN M. HOWARD.
CHARLES J. ALLEN.
